UNITED STATES PATENT OFFICE

156,849

TOY KITTEN

Florence Joan Schippert, Philadelphia, Pa.

Application March 31, 1949, Serial No. 1,725

Term of patent 14 years

(Cl. D34—2)

To all whom it may concern:

Be it known that I, Florence Joan Schippert, a citizen of the United States, residing at Philadelphia, county of Philadelphia, and Commonwealth of Pennsylvania, have invented a new, original, and ornamental Design for a Toy Kitten, of which the following is a specification, reference being had to the accompanying drawing wherein:

I claim:

The ornamental design for a toy kitten, as shown.

FLORENCE JOAN SCHIPPERT.
